UNITED STATES PATENT OFFICE.

HARRY L. FULTON, OF PUEBLO, COLORADO.

AUTO-SERVICE BULLETIN.

1,336,739.

Specification of Letters Patent. Patented Apr. 13, 1920.

Application filed March 25, 1919. Serial No. 284,966.

To all whom it may concern:

Be it known that I, HARRY L. FULTON, a citizen of the United States, residing at Pueblo, in the county of Pueblo and State 5 of Colorado, have invented new and useful Improvements in Auto-Service Bulletins, of which the following is a specification.

My present invention pertains to auto service bulletins, and relates particularly to 10 a device of this character adapted for use where automobiles and the like are being operated by their owners or employed drivers, also adapted to be used where "taxi", "jitney", or other passenger service 15 is offered, or where an auto is being operated in passenger service over a regular route.

An object of the invention is to provide a service bulletin which is so constructed that 20 it can be mounted in fixed relation against the inner side of the windshield glass of an automobile, and which in very compact form embodies mechanism to be set to indicate the course to be taken by the auto, the starting 25 time, the destination, and the number of passengers who will be accommodated.

A further object resides in so constructing the service bulletin and so marking the same that when no service is offered large areas 30 of solid color in symmetrical relation will be shown, whereas when service is offered these areas of color are broken and show contrasting patches which will draw the eye of a prospective passenger to the particular 35 information of interest.

Yet another object is to arrange, in conjunction with the indicator means to be visible through the glass of the windshield, operating or setting means accessible to the 40 driver or an occupant of the auto, which operating or setting means is indexed so that the bulletin may be set to show any information desired, from the rear, without alighting from the auto to inspect the face.

With these and other objects in view, which will be apparent from the specification, drawings, and claims, this invention includes certain novel features of construction and combinations of parts which will 45 now be set forth.

In the drawings:

Figure 1 is a view in front elevation of my improved service bulletin with the parts set to indicate the offer of service.

Fig. 2 is a view in rear elevation to show

the operating parts and with these parts set in the same relation as indicated in Fig. 1.

Fig. 3 is a view in elevation of the front plate of the body as it would appear if separated from the remaining parts. 60

Fig. 4 is an elevational view partly in section with the front plate removed.

Fig. 5 is a view similar to Fig. 2 with certain of the operating knobs omitted to give a better understanding of the assembly of 65 other knobs.

Fig. 6 is a transverse vertical sectional view on line 6—6 of Fig. 2.

Fig. 7 is a sectional view similar to Fig. 6 taken on line 7—7 of Fig. 2. 70

Fig. 8 is a fragmentary detail view showing indicating disk holding means which may be employed.

The case of my service bulletin is made up of the front and back plates 1 and 2, plate 1 being bent back at its edges and crimped on plate 2 so that the plates are securely connected. The back plate 2 can be finished in any manner desired, the front plate however is preferably coated with a baked 75 enamel or other coloring applied thereto to give the distinctive patches as shown. The main background is preferably painted in green or some other color which will tend to attract attention, a central panel is done 80 in white or some light color which will readily take and show instructions or other printed matter; and for a purpose which will be clear as the description progresses, a small block of red or other color is painted 85 in as shown at 3.

Before assembling the front plate appears substantially as shown in Fig. 3, and this plate is colored as here best indicated, the circular white patches being left on opposite 95 sides of the central panel. Circular openings 4 and 5 are provided in the plate 1 centered within the circular white patches, and around the opening 4 compass or direction markings as indicated at 6 are given, hour 100 designations being marked around opening 5 as indicated at 7. For convenience in reference the white patch having markings 6 thereon will be referred to as the compass dial, and the circular space marked by designation 7 will be called the clock dial. The compass dial has three main points of the compass marked thereon and the four intermediate points are also designated. It is 105 preferable that the main and intermediate 110

points be marked substantially as upon the standard compass and in lieu of the 4th main point the plate has an opening 8. Above the compass dial an elongated opening 9 is provided and below this dial opening 10 is provided.

The clock dial is divided off into thirteen parts, the spot of color at 3 occupying one of these divisions and the remaining divisions being marked from 1 to 12, thus giving the usual hour designations. Below circular opening 5 the plate has an opening 11. The back plate 2 has openings therethrough corresponding substantially to circular openings 4 and 5, and setting knobs 12 and 13 are provided with bearing portions to fit these circular openings so that the knobs are journaled to turn therein, and on knobs 12 and 13 circular disks 14 and 15 are secured. These disks are fixed on the knobs to lie between the front and back plates; and the edge of plate 1 is crimped over the edge of plate 2 at 2', as explained above, after the parts have been assembled so that the various members will be maintained in proper positions.

Setting knobs 12 and 13 are provided with central bearing openings, and spindles 16 and 17 are received to turn in these openings. Spindle 16 has a circular disk 18 fixed at one end thereof so that as this spindle is placed in the bearing opening of knob 12 disk 18 is on the face of plate 1 over the compass dial. Disk 18 is of substantially the same size as the white patch marked off to provide the compass dial, and has a notch 19 therein which corresponds substantially to opening 8 provided through plate 1. Spindle 17 has a disk 20 carried at one end thereof to cover over the white patch on plate 1 which is marked off to show the clock dial, and this disk has a notch 21 in the edge thereof, which notch extends for substantially one-thirteenth of the circumference of the disk. Setting knobs 22 and 23 are fixed on the spindles 16 and 17, and these knobs are marked with designating or indicating characters corresponding to the characters or designations 6 and 7 on the compass and clock dials. Arrow marks are provided on the back plate 2, as shown in Fig. 2, and as knobs 22 and 23 are turned to bring the various markings thereof to the arrow points, the notches 19 and 21 of disks 18 and 20 are located to expose corresponding designations on the dials.

Disk 14 is intended primarily to show the character of service offered, and at diametrically opposite points, where they will be visible through openings 9 and 10, this disk has the words "Going" and "To." Spaced equally from the foregoing words the disk has words "Taxi" and "To," shown thereon, these words being diametrically opposite. As has been stated, the compass dial

has only three of the main points of the compass indicated thereon, opening 8 taking the remaining point, and to supply this deficiency disk 14 has the word "North" marked thereon to be visible through opening 8 when the parts are set as in Fig. 1. This disk also has a patch of red or other color at 24, located to be visible through opening 8 and patches of green or other color, as indicated at 25, to show back of openings 9 and 10. Knob 12 has the designations "G," "O," and "T" thereon to indicate the various settings of the dial 14.

On disk 15 there is a patch of green color at 26, which will show back of opening 11, and for the remainder of the distance around the disk designations are shown to indicate the half hours and quarter hours, these designations being shown in duplicate and differentiated by the markings "A. M." and "P. M." Knob 13 has corresponding designations thereon and is set to the arrow to show desired designations through opening 11. Below the compass dial the metal of plate 1 is cut to form opening 27 and upper and lower flaps of the plate as thus cut are bent back through opening 28 in plate 2 and are bent up to form slide ways 29 and 30. A clip member 31 has side flanges formed to catch slide ways 29 and 30 and retain the clip in place back of opening 27. The clip is preferably tinted green or other color on the inner side so that when no destination is to be indicated the space taken by opening 28 will harmonize with the background, however, the clip is constructed to take a card 32 upon which indication is given of the destination or the end of the trip for which service is offered. This clip has the ends thereof rolled at 33 to give thumb holds for moving the clip along the slide ways, and as the clip is movable a card or slip showing destination is more readily placed or removed.

Below the central panel and about in line with opening 27 an opening 34 is cut through plate 2, and on one side of this opening appear the words "Will Take," while at the opposite side is the word "Passengers." A spindle 35 is journaled through the plates of the case above opening 34 and has disk 36 fixed thereon to be visible through the opening. This disk, which may be referred to as the capacity indicating disk, has designations thereon as best shown in Fig. 4, which will fill in and complete the sentence marked adjacent opening 34, so that this will read "Will take 1 to 3 passengers," and the like. Over the marking "No," a green or other patch of color is shown, and thus when the parts are adjusted to indicate that no service is offered, the background shown through opening 34 will blend with the body color on plate 1. Setting knob 37 is fixed on the rear

end of spindle 35 and has setting marks thereon.

- In the use of my improved auto service bulletin, the device will be placed on the inner side of the windshield on an automobile with plate 1 of the case against the glass so that this plate will be visible from the outside, and the operator then has before him the several setting knobs which are in a position to be readily accessible and which through the indicating markings thereon make it possible for the operator to set the bulletin to read as desired without alighting from the auto to see the setting on the forward or indicating side. By using printed cards or slips 32, having a name or names specific to the locality in which the bulletin is being used, any number of different service indicating settings may be given, and as these cards or slips can be very readily printed or written out, the bulletin is used with the same efficiency in both directions over a given route and in a number of other connections.
- When the bulletin is set to offer service, the disclosure in Fig. 1 illustrating a specimen setting, any general information on the central panel will be conspicuously displayed, and the special information will be shown in a manner to attract the attention of a prospective passenger. Further, the special information is arranged to read coherently and will be readily understandable even though read at a glance, as when the machine is in motion. In the present setting, the bulletin conveys the information that the auto is "Going north to Denver," "Will take 1 to 3 passengers," and starts at "10.30 P. M."
- When no service is offered knobs 12, 13, 22, and 23, are set to "O," knob 37 is set to "No," and card 32 is removed from the position back of opening 27. With this setting of parts, all bulletin indications are eliminated with the exception of that reading "Will take no passengers." In the circular spaces included by disks 18 and 20 solid patches of red are shown, and the background including that shown through openings 9, 10, 11, 27, and 34, is a solid body color. When service is offered, attention is particularly attracted to the bulletin readings by reason of the fact that this solid body color is broken by white patches having the service stating printing therein.

In Fig. 8 I have illustrated means by which the disks are held in set relations, however, as this is only one form of means which might be employed in this connection, and as the function and operation will be readily apparent I shall not here go into detail.

From the foregoing it will be seen that I have provided an auto service bulletin which is of such construction that information

which it is desired to present to prospective passengers or to the public generally is given and displayed with concise and distinct particularity; and, while I have described specific embodiments and have mentioned only certain possible modifications it will be appreciated that in practice I do not limit myself to such specific details as are herein set forth, but may resort to any practical modifications falling within the scope 75 of the invention as defined in the appended claims.

I claim:

- An auto service bulletin including with a case to be displayed by an auto, movable parts having service indicating markings arranged to be set to show an offer of service and the service offered, and setting means directly connected with said movable parts by which the indications of the bulletin are changed provided with markings adjacent a fixed point on the case to indicate to an operator settings as made. 80
- An auto service bulletin including with a case to be mounted on an auto, disks mounted in conjunction with said case to be manipulated to display and cover printed information visible from the forward side of the case, and setting means on the back of the case by which said disks are manipulated provided with indicating markings to show to an operator the matter displayed to be visible from the forward side of the case. 90
- An auto service bulletin including with a case to be mounted on an auto, disks mounted in conjunction with said case to be manipulated to display and cover printed information visible from the forward side of the case, setting knobs on the back of the case by which said disks are manipulated, and indicating markings on said knobs corresponding with the information to be displayed. 95
- An auto service bulletin including with a case having openings through the front thereof, disks containing printed matter mounted within said case to be turned to positions to display the printed matter through said openings, and knobs on the back of said case directly connected with and by which said disks are turned provided with indicating markings corresponding to the printing on said disks. 105
- An auto service bulletin including with a case having information to be displayed shown on circular dials on the forward side thereof, disks revolubly mounted over said dials to cover the printed matter thereof and provided with openings through which portions of the information are visible when the disks are turned to different settings. 115
- An auto service bulletin including with a case having information to be displayed shown on circular dials on the forward side 130

thereof and provided with openings adjacent said dials, circular disks revolubly mounted over said dials provided with notches through which portions of the printed matter are visible when said disks are turned to various positions, and disks revolubly mounted within said case to turn adjacent the openings and having information shown thereon to be displayed through 10 said openings.

7. An auto service bulletin including with a case having information to be displayed shown on circular dials on the forward side thereof and provided with openings adjacent said dials, circular disks revolubly mounted over said dials provided with notches through which portions of the printed matter are visible when said disks are turned to various positions, disks revolubly mounted within said case to turn adjacent the openings and having information shown thereon to be displayed through said openings, and means to hold certain of said disks in information displaying positions.

25 8. An auto service bulletin including with a case having information to be displayed shown on circular dials on the forward side thereof, disks revolubly mounted over said dials to cover the printed matter thereof 30 and provided with openings through which portions of the information are visible when the disks are turned to different settings, and setting knobs on the back of said case by which said disks are turned provided 35 with indicating markings to show the setting of the same.

9. An auto service bulletin including with a case having information to be displayed shown on circular dials on the forward side 40 thereof and provided with openings adjacent said dials, circular disks revolubly mounted over said dials provided with notches through which portions of the printed matter are visible when said disks are turned to various positions, disks revolubly mounted within said case to turn adjacent the openings and having information shown thereon to be displayed through said openings, and a setting knob for each of said 50 disks positioned on the back of the case and having indicating markings thereon similar to the corresponding disk and dial markings.

10. An auto service bulletin including 55 with a case having openings through the forward side thereof and adapted to be displayed by an auto with the forward side thereof visible, disks revolubly mounted in said casings with portions visible through the openings thereof, other disks provided with notched openings mounted revolubly on the axes of certain of the first mentioned disks, and markings on the disks within the casing and upon the casing to indicate the offer of service by the auto to-

gether with the direction of travel and destination as well as the number of passengers and the time of starting.

11. An auto service bulletin including with a case to be displayed by an auto and 70 having an opening therethrough, means to frame a card having information as to destination within said opening, means carried by said case to be visible from the forward side thereof to indicate the character of 75 service and direction of travel, means mounted in the case also visible from the forward side to designate the number of passengers to be accommodated, means likewise showing from the forward side to tell 80 the time of starting, and setting knobs at the back of said case by which said direction indicating and the accommodation designating and time telling means are manipulated and set, said knobs having 85 markings thereon to show the settings.

12. An auto service bulletin including with a case to be displayed by an auto made up of front and back plates secured together, the forward plate of said case 90 having circular dials thereon marked with direction and hour indications and provided with openings adjacent said dial and an opening spaced therefrom, disks mounted revolubly within said case having service 95 indicating markings and fraction-of-hour markings thereon to be displayed through the openings adjacent the direction and hour dials respectively, a circular disk revolubly mounted within said case having 100 capacity indicating markings and disposed to show these markings through one of the openings from said dials, disks mounted over said dials revoluble independently of the disks within said case and having 105 notched openings through which the markings of said dials are shown, and a setting knob for each of the disks carried at the back of said case and having markings thereon to show the settings of said disks. 110

13. An auto service bulletin including with a case to be displayed by an auto made up of front and back plates secured together, the forward plate of said case having circular dials thereon marked with direction and hour indications and provided with openings adjacent said dial and an opening spaced therefrom, disks mounted revolubly within said case having service 115 indicating markings and fraction-of-hour markings thereon to be displayed through the openings adjacent the direction and hour dials respectively, a circular disk revolubly mounted within said case having capacity indicating markings and disposed to show these markings through one of the openings from said dials, disks mounted over said dials revoluble independently of the disks within said case and having 120 notched openings through which the mark- 125

ings of said dials are shown, a setting knob for each of the disks carried at the back of said case and having markings thereon to show the settings of said disks, said front 5 plate being tinted in a distinctive color and the disks covering said dials being colored to contrast, said front plate having spots of the hue of said colored disks to show through the notches thereof and complete 10 the circular patches of contrasting color and the remaining disks having spots of color thereon to be shown back of the openings of the front plate and to complete the solid ground color thereof when no service 15 is offered.

14. An auto service bulletin including with a case to be displayed by an auto made up of front and back plates secured together, the forward plate of said case 20 having circular dials thereon marked with direction and hour indications and provided with openings adjacent said dial and an opening spaced therefrom, disks mounted 25 revolvably within said case having service markings and fraction-of-hour markings thereon to be displayed through the openings adjacent the direction and hour dials respectively, a circular disk revolvably mounted within said case having capacity indicating markings and disposed 30 to show these markings through one of the openings from said dials, disks mounted over said dials revolvable independently of the disks within said case and having notched openings through which the markings of said dials are shown, a setting knob 35 for each of the disks carried at the back of said case and having markings thereon to show the settings of said disks, said case having an opening through the front and 40 back plates thereof, and a clip to hold a card having a destination marking thereon framed within said opening.

In testimony whereof I affix my signature.

HARRY L. FULTON.
